Primary Examiner — David Muller*Assistant Examiner* — Nathan Johnston(74) *Attorney, Agent, or Firm* — Notaro, Michalos & Zaccaria P.C.**CLAIM**

The ornamental design for a table caddy, as shown and described.

DESCRIPTION

FIG. 1 is a top, front, right perspective view of a table caddy showing my design therefor;

FIG. 2 is a top plan view thereof;

FIG. 3 is a front elevational view thereof;

FIG. 4 is a side elevational view thereof;

FIG. 5 is a sectional view taken along line 5-5 of FIG. 2 thereof;

FIG. 6 is a sectional view taken along line 6-6 of FIG. 2 thereof;

FIG. 7 is a sectional view taken along line 7-7 of FIG. 2 thereof;

FIG. 8 is a sectional view taken along line 8-8 of FIG. 2 thereof;

FIG. 9 is a bottom, front, left perspective view thereof; and,

FIG. 10 is bottom plan view thereof.

Throughout the drawings the broken lines form no part of the design.
